UNITED STATES PATENT OFFICE.

LELAND F. BURNHAM, OF PITTSBURGH, PENNSYLVANIA; LESTER H. KEIM, OF LOS ANGELES, CALIFORNIA; AND CARL SCHAFER, OF ALLISON PARK, PENNSYLVANIA, ASSIGNORS TO WESTINGHOUSE ELECTRIC AND MANUFACTURING COMPANY, A CORPORATION OF PENNSYLVANIA.

TROLLEY BASE.

Application filed October 10, 1925. Serial No. 61,691.

Our invention relates to trolley bases, more particularly to trolley bases for current collectors that are utilized on electric railway vehicles.

5 It is among the objects of our invention to provide a trolley base of improved design which shall be of simple, compact and durable mechanical construction.

Another object of our invention is to provide a trolley base for current collectors which shall be provided with improved locking means for maintaining the pole member in a horizontal position, and which shall embody a buffer for absorbing the shocks 10 incident to the accidental removal of the collector wheel from the trolley line and for cushioning the pole against sharp impacts when it is manipulated to a raised position.

Another object of our invention is to provide simple means for assembling the several cooperating parts of the base and pole members, whereby ready access to any of the parts subjected to excessive wear is provided for the purposes of replacing or repairing the 15 same.

Heretofore, various forms of trolley bases have been proposed which embody the usual stationary base, a turret member and a hinged pole biased by one or more service springs to 20 maintain a predetermined tension of the collector wheel against the trolley wire.

Our present invention contemplates a trolley base structure in which the several cooperating parts are of improved design for 25 the purpose of obviating the difficulties encountered in the manufacture, assembly and operation of prior types of trolley bases.

In the accompanying drawings, constituting a part hereof and in which like reference 30 characters designate like parts:

Fig. 1 is a plan view of a trolley base, with the service springs partially broken away, embodying the principles of our invention,

Fig. 2 is a view in side elevation thereof,

45 Fig. 3 is an enlarged view of a trunnion member for engaging the buffer spring in our invention,

Fig. 4 is a plan view of a modified form of trolley base embodying the same principles 50 of mechanism and having the same function as the base shown in Fig. 1,

Fig. 5 is an enlarged detail view of a

double spring trunnion employed in connection with the buffer springs,

Fig. 6 is a view, partially in section and 55 partially in side elevation, of the trolley base of Fig. 1, showing the pole raised to the operating position, and

Fig. 7 is a fragmentary view, partially in section, of the trolley base with the pole in 60 the vertical position.

Referring to Figs. 1 and 2 of the drawings, the structure therein illustrated comprises a mounting bracket 1, which is adapted to be secured to the roof of a railway vehicle and to receive a stationary base member or foot 2 that is secured thereto by a plurality of 65 clamping bolts 3. The base 2 encloses a vertically hollow turret post 4, which is adapted to receive a turret 5 for swivelling movement 70 in a horizontal plane.

A plurality of anti-friction roller bearings 6 are disposed between the turret post 4 and the turret or swivel 5 to prevent binding of the swivel member. The upper portion of 75 the turret post 4 is flanged and provided with a circular groove 7, which is in co-operative alignment with a complementary grooved portion 8 of the turret 5 for the purpose of receiving a pin 9 that is held by cotter keys 80 10 to cause the members 4 and 5 to interact, thereby preventing disengagement of the turret and its base.

A pole bracket 11 has a forked portion 12 pivoted to the rearward extending portion 13 85 of the swivel turret 5 by a pin 14. The bracket 11 is provided with a clamping member 15, in which the trolley pole 16 is disposed, being secured by a pair of bolts 17.

The upper portion of the pole bracket 11 is 90 provided with an arm or end bracket 18, having horizontal openings 19 therein for receiving hanger bolts 20 for engaging one end of a pair of service springs 21, the other ends of which are disposed in eyelets 22 that 95 are provided at the rear end of the swivel member or turret 5.

A cylindrical opening 24 extends longitudinally in the upper body portion of the pole bracket 11 for receiving a latch pin 25, 100 which is biased by a coil spring 26 that is located in a recess 27 provided in the swivel member 5. The top surface of bracket 11 is provided with a pair of non-parallel slotted

- openings 28 and 29, which are adapted to receive a thumb latch 30 that is secured transversely of the latch pin 25 and operates to lock the pin 25 in the position shown in Fig. 2
 5 while the pin member 30 is in the slot 28, or against the tension of the spring 26 when the pin 30 is disposed in the slot 29, for, in the first case; locking the trolley pole in a horizontal position that is shown in Fig. 2, and, in
 10 the second case, releasing the pole to permit raising the same against the trolley wire.

A buffer spring 32 is disposed in the rear of the swivel member 5 and is held in proper alignment by a piece of tubing 33 that is secured to the turret extension 13 by a cotter key 34. A trunnion member 35, Figs. 2 and 3, is disposed in an elongated opening 36 that is provided in the extension 13. The turret 5 is provided with an off-set portion
 20 37 for supporting the end of the tube 33.

The spring member 32 is assembled in the pole bracket in the following manner. The trunnion member 35 is inserted in the slotted opening 36 with the ring portion (see Fig. 3)
 25 thereof lying flat and transversely in the slot. After inserting the member 35, it is turned about its trunnion until the ring portion thereof assumes a vertical position. The spring element 32 is then inserted in the
 30 opening of the swivel frame 5 until the end thereof engages the trunnion member, the tube 33 is then disposed within the coil spring 32 and the ring portion of trunnion member 35 and over offset portion 37 of turret 5, and
 35 the cotter key 34 is inserted in the opening provided at the end of the swivel frame 5, thus holding the trunnion, spring and tube in place.

The structure shown in Fig. 4 is similar
 40 to that shown in Figs. 1 and 2 with the exception that three service springs 31 are utilized for biasing the pole against the trolley wire, and two buffer springs 32 are employed instead of the single member that is utilized
 45 in the structure shown in Fig. 1.

The operation of our device is briefly as follows: The trolley base is assembled as shown in the respective figures of the drawing and the trolley pole is disposed in any desired
 50 position, that is, either locked in the horizontal position that is shown in Fig. 2, by means of the locking element including the pin 25, or it may be raised against the trolley wire by releasing the pin 25 from the recess 28 and placing it in the recess 29 of the bracket 11. In either the locked or the released position, the turret member 5 is free to turn on the base 2, and the turret is maintained in its proper vertical alinement with the base by the interaction of the grooves 7 and 8 with the pin member 9. The action of the buffer spring 32 is such that, when the pole 16 is suddenly raised, the trunnion member 35 engages the forked portion 12 of the pole bracket 11 against the tension of the spring
 60 65

32, thus cushioning the impact resulting from such sudden engagement and thereby relieving the joints and other parts of the trolley base from severe strain.

It is evident from the foregoing description of our invention that trolley bases made in accordance therewith provide simple and compact supports for current-collector devices which are relatively inexpensive to manufacture and efficient in their operation.

Although we have described two embodiments of our invention, it will be obvious to those skilled in the art that further modifications may be made in the details of construction and the proportioning and arrangement of the several co-operating parts without departing from the principles herein set forth.

We claim as our invention:

1. The combination, in a trolley base, of a foot for mounting the base on a vehicle roof, a swivel frame carried by said foot, a combination pole and spring bracket pivotally mounted on said swivel frame, and a buffer for yieldingly restraining angular movements of said bracket, said buffer comprising a trunnion member slidingly mounted in an opening in an extended portion of said frame, a spring member disposed in a second opening in said frame in engagement with said trunnion member, a tube disposed within said spring and means for securing said tube and spring in said frame.

2. The combination, in a trolley base, of a foot for mounting the base on a vehicle roof, a swivel frame carried by said foot, a combination pole and spring bracket pivotally mounted on said swivel frame, and a buffer for resiliently restraining angular movements of said bracket, said buffer comprising a trunnion member slidingly mounted in a slotted opening in an extended end portion of said frame, a coil spring member disposed in a second opening in engagement with said trunnion member, a tube disposed within said spring and a cotter key for securing said tube and spring in said swivel frame.

3. The combination, in a trolley base, of a foot, a swivel frame mounted thereon, roller bearings disposed between said foot and swivel to journal the latter for rotation with respect to said foot, a combination spring and pole bracket pivotally mounted on said swivel frame, a trolley pole adapted to be secured in said bracket, and means for locking said pole to said swivel frame in a horizontal position, said means comprising a latch pin slidingly mounted in said pole bracket and adapted to interact with an opening provided in the swivel frame, a spring for biasing said latch pin against the swivel frame and a thumb latch adapted to hold said pin in a locked or unlocked position.

4. The combination, in a trolley base, of a foot having a vertical support with an off-

set flange portion, a swivel frame journalled by a plurality of vertically disposed roller bearings in said support, a key secured in said swivel frame and adapted to engage the off-set portion of said support to maintain said swivel frame in its operative relation to said support, a combined pole and spring bracket pivotally mounted on said swivel frame, service springs connecting said bracket

and swivel frame; a trolley pole secured in said bracket, and a buffer provided in said swivel frame to coact with said pole bracket.

In testimony whereof, we have hereunto subscribed our names the 9th and 24th days of September, 1925.

LELAND F. BURNHAM.
LESTER H. KEIM.
CARL SCHAFER.
